UNITED STATES PATENT OFFICE

WILLIAM DREISEL, OF LAWRENCE, MASSACHUSETTS, ASSIGNOR TO ANDREWS & GOODRICH, INC., OF CAMBRIDGE, MASSACHUSETTS, A CORPORATION OF MASSACHUSETTS

HEAT INSULATING PANEL FOR DRIER HOUSINGS AND THE LIKE

Application filed April 9, 1931. Serial No. 528,739.

This invention relates to a heat-insulating panel which is suitable for use in building the walls, floors or roofs of drying ovens, heated or cooled chambers and similar devices, and especially to a so-called "metal panel" which comprises a metal envelope with or without a filling of heat-insulating material. In the following specification and claims, the above-described walls, floors, or roofs of drying ovens, heated or cooled chambers, and similar devices will be spoken of as a housing.

In building housings with panels of this type it has been customary to erect a supporting framework and then to secure the panels to the framework.

It is one of the objects of my invention to provide a metal panel of a novel construction which has sufficient inherent rigidity and strength so that a housing or the like can be made by simply securing the panels together without the necessity of erecting a supporting framework to give strength to the completed structure. The inherent rigidity and strength of the panels provides all the strength necessary for the completed structure.

My improved panels are each made with the usual metal envelope which may or may not be filled with heat-insulating material, but which is constructed with strength-giving panel flanges which stiffen the panel and give it sufficient inherent rigidity and strength so that when the panels are connected together to form the housings, the latter will be self supporting, the panels themselves having all the strength necessary for supporting the structure and making it rigid thus obviating the necessity of using any supporting framework.

In the preferred embodiment of my invention each panel is made so that the strength-giving panel flanges thereof are located at the edges that are in engagement with or meet adjacent panels in the completed structure and these flanges are made so that they not only give the required strength to the panels but also can be used for fastening adjacent panels together.

In order to give an understanding of the

invention I have illustrated in the drawings a selected embodiment thereof which will now be described after which the novel features will be pointed out in the appended claims.

Fig. 1 is a perspective somewhat diagrammatic view illustrating a housing made in accordance with my invention; 55

Fig. 2 is an enlarged sectional view on the line 2—2, Fig. 1;

Fig. 3 is an enlarged sectional view on the line 3—3, Fig. 1;

Fig. 4 is a perspective view on a reduced scale showing one of the side panels with a part removed;

Fig. 5 is a similar view showing one of the roof panels also with a part removed; 65

Fig. 6 is a fragmentary sectional view showing a different embodiment of the invention.

As stated above the metal panels embodying my invention are of the type comprising a metal envelope of the proper size and shape which may or may not be filled with some heat-insulating material. Some of these panels are made to be used as side wall panels and other panels as roof panels. The panels may also be used for floors. The side wall panels, one of which is indicated at 1, Fig. 2, is made with the two opposed sheet metal sides 2 and 3 which form the side faces of the panel, which sides are spaced from each other and which are connected at the edges of the panel with sheet metal edge strips. The space between the walls 2 and 3 may be filled with some suitable heat-insulating material 4, of which mineral wool constitutes an example, or may simply be left void as an air space. 70

In the present embodiment of the invention the edge strips which enclose the edges of each panel are formed to present the stiffening panel flanges that give stiffness and rigidity to the panel, these flanges also being used for connecting or fastening the adjacent panels together, by means of bolts, rivets, clips or any other suitable way. 75

The edge strip along the bottom edge of each side wall panel is indicated at 5 in Figs. 2 and 4, that along each side edge of each panel at 6 in Fig. 3, and that along the top edge of each side wall panel at 7 in Figs. 2 80 100

and 4. Each of these edge strips not only encloses the edge of the panel but also provides a stiffening flange along said edge. As herein shown the bottom of each side face 2, 3 is bent outwardly to form the flange 8 which rests on the bottom edge strip 5 and the edges of this strip 5 are bent over the flanges 8 as shown at 9. There is thus provided a three-ply panel flange 10 along the bottom of the panel 1 on each side thereof.

10 The vertical edges of each sheet 2, 3 of any side wall panel are also bent to form the outwardly-extending flanges 11 and the vertical edge strip 6 of each panel overlies these flanges 11 and has its edges 12 bent around the flanges. There is thereby provided at each vertical edge of the panel two outwardly-directed three-ply strength-giving panel flanges 13.

20 The adjacent panels 1 forming the side wall of a housing are placed edge to edge with the flanges 13 of one panel overlying those of an adjacent panel and the panels are connected together by suitable fastening devices which connect the overlying flanges. 25 While any suitable fastening devices may be employed I prefer to use bolts 14 which extend through the overlying panel flanges 13 as shown best in Fig. 3.

30 The panel flanges 13 give stiffness and rigidity to the panels so that when the side wall panels are placed edge to edge and are bolted together the structure is substantially as strong as if they were formed with a 35 skeleton framework to which the panels are secured.

The edge strips 7 at the top edge of the side wall panels have the same general features as described with reference to the vertical edge strips 6 except that the top edge of each panel is preferably made at a mitre of 45° so as to fit the correspondingly-shaped edges of the roof panels 15.

40 The upper face of the outside sheet 2 of a panel 1 is bent outwardly to form a flange 16 and the upper edge of the inside sheet 3 is similarly bent to form a flange 17. The inside sheet 3 terminates somewhat below the outside sheet 2 and the flange 17 extends 45° at about a 45° angle from the sheet 3. The top edge strip 7 has its edges 18 folded about the flanges 16 and 17 thereby producing strength-giving panel flanges 19 which extend along the upper edge of the panel on each 50 side thereof. The inner flange 19 extends at a 45° angle while the outer flange 19 may extend at right angles to the face of the panel.

55 The roof panels 15 have the same general construction as the side wall panels, that is, each roof panel has the two sheet metal side faces 20 and 21 which are spaced apart with an air space between them which may, if desired, be filled with the insulating material 4. The marginal portions of the sheet metal faces 20 and 21 are bent outwardly to form

flanges and the edges of each roof panel are closed by edge strips 22 similar to the edge strips 5, 6, 7 of the wall panel. The ends of each roof panel 15 are mitred as shown in Fig. 2, this being accomplished in the same way that the upper ends of the wall panels are mitred. Each roof panel, therefore, will be formed along the ends and sides with the three-ply ribs or panel flanges. The three-ply flanges at the sides are indicated at 23 70 and those at the mitred panels at 24 and 25.

75 The three-ply panel flange 24 is shown as extending at an angle of 45° while the three-ply panel flange 25 is illustrated as being situated in substantially the plane of the upper 80 face of the roof panel. When the roof panels and side panels are being assembled to build a housing the three-ply flanges 25 of the roof panels will overlie the flanges 19 of the side wall panels and the angular flanges 24 of the 85 roof panel will meet and overlie the angular flanges 19 on the inside of the side wall panel. An advantage resulting from making the panel flanges in edge strips which are separate from but connected to the side walls 90 of the panel is that it is possible to increase the strength of the panel by using heavier gauge metal for the edge strips and without changing the thickness of the metal of the side walls. In the case of panels having a 95 long span the necessary strength may be given to the panels and panel flanges to support the structure without the use of a framework by simply using edge strips of the proper 100 thickness and depth.

105 Another advantage resulting from applicant's construction is that increased strength may be given to the panels by so arranging the edge strips as to provide increased depth of panel flanges without, however, changing the thickness of the panel.

110 The panels are connected by fastening the flanges together by means of some suitable fastening devices. In the illustrated embodiment of the invention fastening devices in the form of bolts are used and as shown in Fig. 2 the overlying flanges 19 and 25 are bolted together by the bolts 26.

115 The side wall panels which are located at the vertical corners of the completed structure will preferably be made with the mitred or bevelled vertical edges as shown in Fig. 3 with reference to the panels 1a, 1b. In the panel 1a the vertical edge strip 6a is arranged at an angle to the side sheets 2 and 3 and similarly the vertical edge strip 6b of the panel 1b has an angular arrangement. When, therefore, these panels are assembled a mitred corner will be provided.

120 The edge or end strips at the meeting edges of two panels are preferably constructed to have an interlocking engagement. For this purpose the edge strip 6 on one vertical edge of a panel may be formed with a groove 27 and the edge strip 6 on the meeting edge of 125

the adjacent panel will be provided with a rib 28 adapted to fit into the groove 27.

In assembling the panels I will preferably place a suitable cement 29 in the groove 27 so that when any two adjacent panels are clamped together by the bolts 14 a tight joint will be made between said panels.

In order that the panels may continue to function properly it is important that if insulating material 4 is used it should be prevented from settling in the vertical panels and should remain evenly distributed throughout each panel.

One way to provide for this is to make the side sheets 2 and 3 of the panels with horizontally-extending indentations 30 which produce horizontal ribs on the inside of the side sheets. These ribs are located opposite each other thereby providing a restricted space between each pair of opposed ribs. These restricted places serve to prevent the insulation 4 from settling in the panel and thus maintain it evenly distributed without, however, reducing unduly the amount of insulation between the ribs. The ribs 30 also strengthen the panels in a lateral direction.

Where the indentations 30 are employed I will preferably cut out the vertical flanges 11 at the edges of the side sheets 2 and 3 at the places wherein the indentations 30 occur as shown at 31 in Fig. 4.

In Fig. 6 I have shown a different way of holding the insulation in position. In this embodiment of the invention the side sheets 2 and 3 are formed with ribs 32 opposite each other thereby producing grooves on the inner sides of the sheets. Suitable strips of wire mesh or other material 33 may be retained in said grooves thereby providing the means for retaining the insulation 4 in position.

I may, if desired, place spacing blocks 34 between the side walls 20 and 21 of the roof panels 15 so that if any weight is applied to any roof panel a portion thereof will be transferred to and sustained by the lower face 20 of the panel.

With this construction the vertical panel flanges 13 of the side wall panels perform the function of posts and thus import into the structure all the necessary strength and rigidity to support the structure. Similarly, the panel flanges 23 of the roof panels reinforce and strengthen the latter and perform the function of girders or beams. Thus the panel flanges of the wall panels and the panel flanges of the roof panels take the place of the supporting framework which has heretofore been used in this type of housing construction.

In making the roof panels it is, of course, necessary that the flanges 23 thereof should have sufficient strength to properly support the roof and if the roof has a long span or is subjected to additional weight the edge strips of the roof flanges may be made of

heavier gauge metal and with sufficient depth to furnish the necessary strength.

The panels embodying my invention are adapted for building heat-insulating walls or partitions or entirely closed structures including a roof and floor and such walls or partitions or structures are made by simply fastening the appropriate panels together and without the necessity of erecting any framework for supporting the panels since the panel flanges of the panels provide all the strength necessary to support the structure without the use of a supporting framework.

If the housing to be built has a transverse dimension no greater than the length of a roof panel then a roof panel having a mitre shape at each end may be employed. If, however, the transverse dimension of the housing is greater than the length of one panel then the span across the housing from one side wall to the other would require two or more connected panels. Where this is the requirement the roof panels would be made as shown in Fig. 5 with one end mitred and the other end made in the same way as the bottom or side edges of the side wall panels thereby producing the plural-ply panel flanges 35 which may be connected to the flanges at the end of the adjacent panel.

I claim.

1. A heat-insulating panel for use in building heat-insulating housings, said panel comprising two sheet metal sides spaced from each other, edge strips closing the edges of the panel and secured to the sides, said edge strips forming laterally-extending panel flanges at the edges of the panel which provide means for connecting adjacent panels in the completed structure and which give the panel sufficient strength to make the structure self-supporting.

2. A heat-insulating panel for use in building heat-insulating housings, said panel comprising two sheet metal sides spaced from each other, edge strips closing the edge of the panel and secured to the sides, said edge strips forming a plurality of panel flanges at one or more edges of the panel, which flanges provide means for connecting adjacent panels in the completed structure and give the panel sufficient strength to make the structure self-supporting.

3. A heat-insulating panel for use in building heat-insulating housings, said panel comprising two sheet metal sides spaced from each other, the marginal portion of each being bent outwardly to form a flange, edge strips closing the edges of the panel, said edge strips overlying the flanges and being connected thereto, the flanges and the portions of the edge strips overlying them providing plural-ply panel flanges at the edges of the panel which provide means for connecting adjacent panels in the completed

housing, and which give the panels sufficient strength to make the structure self-supporting.

4. A heat-insulating panel for use in building heat-insulating housings, said panel comprising two sheet metal sides spaced from each other, edge strips closing the edges of the panel and secured to the sides, said edge strips being bent to form laterally-projecting 10 panel flanges which extend along the edges of the panel when in erected position and which constitute means by which the adjacent panels of the wall are connected together and which give the panel sufficient strength 15 to make the structure self-supporting.

5. A heat-insulating panel for use in building heat-insulating housings, said panel comprising two sheet metal sides spaced from each other, edge strips closing the edges of 20 the panel and secured to the sides, said edge strips being bent to form two oppositely-directed panel flanges at each edge, the panel flanges of one panel mating those of an adjacent panel, and means connecting the mating 25 flanges together.

6. A heat-insulating panel for use in building heat-insulated housings, said panel comprising two sheet metal sides spaced from each other, heat-insulating material between 30 said sides, the marginal portion of each side being bent outwardly to form a flange, edge strips closing the edges of the panel, said edge strips overlying the flanges and being connected thereto, the flanges and the portions of the edge strips overlying them providing plural-ply panel flanges at the edges 35 of the panel which provide means for connecting adjacent panels in an erected wall and impart to the panels sufficient strength 40 to support the structure of which the wall is a part.

7. A heat-insulating panel for use in building heat-insulated housings, said panel comprising two sheet metal sides spaced from 45 each other, the marginal portion of each side being bent outwardly to form a flange, edge strips closing the edges of the panel, the marginal portions of said edge strips being folded about said flanges thereby to produce 50 three-ply panel flanges at the edges of the panel which provide means for connecting adjacent panels in a completed housing and give the panels sufficient strength to make the structure self supporting.

8. A heat-insulating wall comprising a plurality of connected individual panels arranged edge to edge, each panel having two spaced sheet metal sides, the marginal portions of the sides being bent outwardly to 60 form flanges, edge strips forming the edges of each panel, the marginal portions of the edge strips being folded about said flanges thereby to provide each panel with outwardly-directed three-ply panel flanges, the abutting 65 edges of adjacent panels having inter-

locking relation, and means to clamp together the panel flanges of adjacent panels, said panel flanges giving the panels sufficient strength to support the structure.

9. A heat-insulating housing, the walls of 70 which are formed of a plurality of connected individual panels each arranged edge to edge, each panel having two spaced sheet metal sides, the marginal portions of the sides being bent outwardly to form flanges, edge 75 strips forming the edges of each panel, said edge strips overlying the flanges and being connected thereto, said flanges and the portions of the edge strips overlying them providing plural-ply panel flanges at the edges 80 of the panel, means to clamp together the panel flanges of adjacent panels with the edge strips on the meeting edges of the adjacent panels in engagement with each other, one of said edge strips having a groove extending 85 longitudinally thereof and the other edge strip having a rib fitting the groove.

10. A heat-insulating panel for use in building heat-insulated walls comprising a metal envelope and heat-insulating material 90 filling said envelope, the latter being formed with strength-giving flanges which extend vertically of the panel when in erected position and which constitute means by which the adjacent panels of a wall are connected together 95 and which impart to the connected panels sufficient strength to support the structure of which the walls form a part, the opposite side walls of the envelope being provided with oppositely-disposed inwardly-directed ribs forming between them constricted spaces which prevent shifting of the insulating material within the panel.

11. A heat-insulating panel for use in building heat-insulated walls comprising a 105 metal envelope and heat-insulating material filling said envelope, the opposite walls of the envelope being provided with oppositely-disposed inwardly-directed ribs forming between them constricted spaces which prevent 110 shifting of the insulating material within the panel.

12. A housing comprising side walls formed of individual heat-insulating panels secured together and a roof portion also formed of individual heat-insulating panels, the roof panels having abutting relation, and each panel having two side walls spaced from each other and edge strips closing the edges of the panel and connecting the walls, 120 said edge strips being separate from the side walls and provided with laterally-extending panel flanges at the edges of the panel, means for fastening said flanges together, said flanges giving the panel sufficient strength 125 to support the roof and thus taking the place of beams or girders for this purpose.

13. A heat-insulating panel for building heat-insulated walls, comprising a metal envelope, heat-insulating material filling said 130

envelope, the opposite walls of said envelope being formed with grooves, and a baffle member supported in said grooves and operating to prevent shifting of the insulating material within the panel.

14. A housing having its walls formed of individual heat-insulating panels secured together, each panel having two side walls spaced from each other and edge strips closing the edges of the panel and secured to the sides, said edge strips forming laterally-extending panel flanges at the edges of the panel which provide means for connecting adjacent panels in the completed structure, the meeting edges of the panels at the corners of the structure having a mitred construction.

15. A heat-insulating wall comprising a plurality of connected individual panels arranged edge to edge, each panel comprising two sheet metal sides spaced from each other, edge strips closing the edges of the panel and secured to the sides, said edge strips forming laterally-extending panel flanges at the edges of the panel, and means connecting the flanges of one panel to those of an adjacent panel, the edge strips at the meeting edges of any two adjacent panels having complementary shapes by which they are interlocked together.

In testimony whereof, I have signed my name to this specification.

WILLIAM DREISEL.
